US00D674346S

(12) **United States Design Patent**
Hashimoto

(10) **Patent No.:** US D674,346 S
(45) **Date of Patent:** ** Jan. 15, 2013

(54) **ELECTRICAL COAXIAL CONNECTOR**

(75) Inventor: **Yoichi Hashimoto**, Tokyo (JP)

(73) Assignee: **Dai-Ichi Seiko Co., Ltd. (JP)**

(**) Term: **14 Years**

(21) Appl. No.: **29/413,939**

(22) Filed: **Feb. 22, 2012**

(30) **Foreign Application Priority Data**

Aug. 30, 2011 (JP) 2011-019504

(57) **CLAIM**

The ornamental design for an electrical coaxial connector, as shown and described.

DESCRIPTION

FIG. 1 is a front, top and left side perspective view of an electrical coaxial connector showing my new design;
FIG. 2 is a front, bottom and left side perspective view thereof;

FIG. 3 is a top plan view thereof;

FIG. 4 is a front view thereof;

FIG. 5 is a bottom view thereof;

FIG. 6 is a rear view thereof; and,

FIG. 7 is a right side view thereof, the left side view is a mirror image thereto.
